UNITED STATES PATENT OFFICE

164,646

SPOON OR THE LIKE

Norman J. Mercer, Brooklyn, N. Y.

Application September 8, 1950, Serial No. 12,107

Term of patent 14 years

(Cl. D54—12)

To all whom it may concern:

Be it known that I, Norman J. Mercer, a citizen of the United States and a resident of Brooklyn, county of Kings, and State of New York, have invented a new, original, and ornamental Design for a Spoon or the like, of which the following is a specification, reference being had to the accompanying drawings, forming part hereof and in which:

Fig. 1 is a front elevational view of a spoon, showing the essential features of my new design in full lines.

Fig. 2 is a side elevational view.

Fig. 3 is a rear elevational view.

My design is shown as delineated in a spoon

but it is to be applied to knives, forks and similar articles of tableware.

I claim:

The ornamental design for a spoon or the like, substantially as shown and described.

NORMAN J. MERCER.
